NECKTIE

Frank D. Cheney and Albert Tedford, Manchester, Conn., assignors to Cheney Brothers, Manchester, Conn., a corporation of Connecticut

Application August 14, 1941, Serial No. 406,782

5 Claims. (Cl. 2—146)

This invention relates to neckties and particularly to neckties of the four-in-hand type.

An object of the present invention is to provide a necktie that when tied will have a tendency to be formed with a central dimple or longitudinal fold extending rearwardly immediately below the knot.

A feature that enables the above object to be accomplished is that the lining is formed of a strip of relatively stiff flat textile material which is compressed or indented along generally longitudinally extending lines one of which is centrally disposed and indented from the outer or front surface of the lining and there being preferably two or more additional lines extending generally parallelly to the side edges of the lining indented from the opposite surface of the lining.

Another object of the invention is to form the lines in the lining strip by compressing the fabric forming the lining by means of a hot iron, or other compressing or embossing means, having an edge formed thereon to indent or emboss a length of the lining extending far enough longitudinally to include the entire knot forming portion of the tie. The central line is indented from the front surface of the lining toward the rear surface and the lateral lines are indented from the rear surface of the lining toward front.

Another feature of the invention is to give the lining a natural tendency to pleat or fold along the indented lines of compression formed therein, the lining however not being actually pleated along the compressed lines so that with each tying of the necktie a natural dimple or fold will be formed below the knot disposed centrally and extending vertically below the knot.

And finally it is an object of the invention to provide the tie just below the knot with a tendency for its side edges to fold or turn backward, to accomplish this result lines of compression are formed closely adjacent and parallel to the side edges of the lining.

With the above and other objects in view, the invention includes the features of construction and operation set forth in the following specification and illustrated in the accompanying drawing.

In the accompanying drawing annexed hereto and forming a part of this specification, we have shown the invention embodied in a conventional form of four-in-hand tie but it will be understood that the invention can be otherwise embodied and that the drawing is not to be construed as defining or limiting the scope of the 55

invention, the claims appended to this specification being relied upon for that purpose.

In the drawing:

Fig. 1 is a front view of a necktie made in accordance with the present invention and completely made up to show the necktie as worn;

Fig. 2 is a view of the lining material used in making the necktie;

Fig. 3 is a cross sectional view of the lining taken through the knot tying portion thereof on the plane of line 3—3 in Fig. 2 before tying;

Fig. 4 is a view similar to Fig. 3 and showing additional indented lines of compression;

Fig. 5 is a cross sectional view of the completely made-up necktie taken on the line 4—4 of Fig. 1; and

Fig. 6 is a vertical sectional view of compression line forming irons adapted when pressed together with a lining fabric between them to indent or compress the lining along longitudinally extended lines.

Briefly, and in its broadest aspect, the invention includes a necktie having an elongated strip of lining material tapered as shown and covered by the ornamental fabric of the necktie, the necktie fabric being folded about the lining strip and loosely stitched thereto, the lining also being indented longitudinally at its knot tying portion by a central line pressed or indented into the lining from the front surface, and preferably also by lines on either side of the center line pressed or indented into the lining from the rear surface.

Referring more in detail to the figures of the drawing there is shown in Fig. 1 a necktie or cravat formed of suitable ornamental textile material 10 and made up and knotted or tied the usual manner as a four-in-hand. Enclosed within this fabric 10 is an elongated strip 11 of relatively stiff textile material extending substantially the length of the necktie. These members 10 and 11 of the necktie are made as usual in four-in-hand neckties and are loosely stitched together longitudinally in the usual manner.

At the knot tying portion of the lining 11 and before being stitched to the fabric 10 the lining is pressed or embossed centrally and longitudinally as shown at 12 preferably by indenting the lining along this line as with the edge of or projection on an iron or die.

Also, and in the same operation the compressed lines 13 are also formed by indenting them into the rear surface of the lining in the same manner. If desired, additional lines as

shown at 15 may also be formed when forming the indentations 13.

As shown in Figs. 2 and 3, in addition to the central compressed line 12, the lining 11 may be indented or embossed laterally with respect to the central line 12 as at 13. These lateral lines 13 may extend in directions parallel to the lateral edges of the lining 11, or parallel to center line, and are indented from the back surface of the lining as indicated most clearly in Fig. 3. The tendency to fold or pleat upon these lines 13 is therefore reversed with respect to the central line 12 and tends to curl the side edges of the tie rearwardly.

The lines 12 and 13 may preferably be formed in the lining by compressing or indenting relatively narrow and elongated areas of the lining between upper and lower embossing irons. These irons 17 and 16 as seen in Fig. 6 have projections 18 formed thereon to compress the lining material 11 along the lines indicated in Figs. 3 or 4. The projections 18 may be of half round cross section and of a diameter to form the desired curved form of indentation. It will be noted that the projections 18 serve to compress the lining but do not pleat or fold the lining material for the reason that the pressure of the projections 18 is against a solid plane surface on the iron opposite the projection.

In knotting the necktie the outer fold at and below its knot tying portion by reason of the indented or embossed longitudinal lines in the lining at that portion, tends naturally to bend or fold to form a central rearwardly extending depression or "dimple" without there being any sharp edges. Also the lateral portions of this outer fold between the central line and lateral edges and along the lines 13 form oppositely disposed folds forwardly extending and increasing the effect of the central depression or dimple.

We claim as our invention:

1. A necktie of the four-in-hand type comprising a tie fabric, and a lining therefor, said lining having a central longitudinally indented line compressed therein at its knot tying portion, whereby said tie when knotted forms a central depression within the fold below the knot.

2. A necktie of the four-in-hand type comprising a tie fabric and a lining enclosed by said fabric, said lining having a central longitudinally indented line compressed therein from its front surface at its knot tying portion, whereby said tie when knotted forms a central depression within the fold below the knot.

3. A necktie of the four-in-hand type comprising a tie fabric and a lining of relatively stiff textile material, said lining having a central longitudinally indented line compressed therein at its knot tying portion, and lateral generally longitudinal lines being indented therein adjacent said central line and compressed from the opposite surface of the lining fabric.

4. A necktie of the four-in-hand type comprising a tie fabric and a lining of relatively stiff textile material, said lining having a central longitudinally indented line compressed at its knot tying portion within its front surface, and lateral generally longitudinally indented lines compressed into the rear surface of the lining on opposite sides of said central line.

5. A necktie of the four-in-hand type comprising a tie fabric and a lining of relatively stiff textile material, said lining having a central longitudinally indented line compressed at its knot tying portion into its front surface, and pairs of longitudinal lines compressed into the rear surface of the lining on opposite sides of said central line.
